UNITED STATES PATENT OFFICE

MAX PAUL VOGLER, OF NASHVILLE, TENNESSEE, ASSIGNOR TO WALTER FRED HOSEIERY
MILLS, INC., OF NASHVILLE, TENNESSEE, A CORPORATION OF DELAWARE

DESIGN FOR HOSEIERY

Application filed September 2, 1931. Serial No. 40,988. Term of patent 3½ years.

To all whom it may concern:

Be it known that I, MAX PAUL VOGLER, a citizen of the United States, residing at Nashville, in the county of Davidson and State of Tennessee, have invented a new, original, and ornamental Design for Hosiery, of which the following is a specification, reference being had to the accompanying drawings, forming a part thereof.

In the drawings, Fig. 1 is a side view of a stocking showing my new design, and

Fig. 2 an enlarged view of a portion of the top of the stocking showing the design more in detail.

I claim:

The ornamental design for hosiery, as shown.

MAX PAUL VOGLER.
